2 SHEETS--SHEET 2.

UNITED STATES PATENT OFFICE.

SPENCER B. WILLIAMS, OF PETERSBURG, VIRGINIA.

DUMPING BASKET.

Application filed August 3, 1921. Serial No. 429,573.

To all whom it may concern:

Be it known that I, SPENCER B. WILLIAMS, a citizen of the United States, residing at Petersburg, in the county of Dinwiddie and State of Virginia, have invented certain new and useful Improvements in Dumping Baskets, of which the following is a specification, reference being had to the accompanying drawings.

This invention relates to certain improvements in dumping baskets and has relation more particularly to a device of this general character especially designed and adapted for use in connection with harvesters, and it is an object of the invention to provide a novel and improved device of this general character including a normally closed swinging wall together with means coacting therewith to move the wall into open or discharging position when the load within the basket and imposed upon the bottom reaches a predetermined weight.

Another object of the invention is to provide a novel and improved device of this general character including a movable wall together with means operating automatically to move intermittently the bottom into open or discharging position.

The invention consists in the details of construction and in the combination and arrangement of the several parts of my improved dumping basket whereby certain important advantages are attained and the device rendered simpler, less expensive and otherwise more convenient and advantageous for use as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan illustrating a basket constructed in accordance with an embodiment of my invention together with the mechanism associated therewith.

Figure 2 is a longitudinal vertical sectional view taken through the structure as illustrated in Figure 1.

Figure 3 is a view in side elevation of the structure as herein disclosed, and

Figure 4 is a fragmentary sectional view taken substantially on the line 4—4 of Figure 3, certain of the parts being omitted.

As disclosed in the accompanying draw-

ings, M denotes the rear portion of a portable frame and particularly of the type disclosed in my application for patent in harvesting machines executed on even date 60 herewith and with which my improved dumping basket as herein disclosed is adapted to be employed. Associated with the frame M is an elevator mechanism E also of the type disclosed in the aforesaid mentioned application and which mechanism includes a transversely disposed shaft 46, rotatably supported by the rear end portions of the side members 6 comprised in said frame M. Each end portion of the shaft 46 extends through a boxing or housing 47, the outer face of said boxing or housing being closed by a removable plate 48. Each end portion of the shaft 46 extends outwardly of the adjacent boxing or housing 47 and has fixed thereto a trip wheel 49. Coacting with each end portion of the shaft 46 is a driving shaft 78, the same being operatively connected within the housing or boxing 47 by the intermeshing gears 76 and 77.

The rear end portion of each of the side members or beams 6 is provided with a depending block 1 which has secured by the rod 3 the end portions of the bottom frame F of the basket 51. This bottom frame F is substantially U-shaped in form and extends rearwardly of the frame M and in substantially a horizontal position. F' denotes the upper frame of the basket 51 and is preferably of the same configuration and dimensions and positioned directly thereabove, with the extremities of the frame F' bolted or otherwise secured, as at 4, to the rear portions of the side members or beams 6. The frames F and F' at substantially equidistantly spaced points thereof are connected by the vertically disposed slats or stiles 5. The lower portion of each of the stiles 5 is disposed inwardly on a predetermined incline and is secured at its lower end portion to an inwardly directed bolt 7 carried by the lower frame F. Surrounding the bolt 7 and interposed between the frame F and the stile 5 is a spacing sleeve 8.

A wall 50, herein disclosed as the bottom wall of the basket 51 comprises an elongated member or beam 9 extending transversely of the frame M between the side members 6 and which is downwardly offset, as at 10, adjacent each end to bridge or straddle the lower end portion of the adjacent block 1. The outer leg 11 of each of the off set por-

tions 10 is pivotally engaged with the rod 3 whereby the member 9 is capable of swinging movement. The upper end of each of the outer legs 11 is continued by an outwardly directed extension or arm 12 terminating in an upstanding member or post 14.

Pivotedly engaged, as at 16, with the upstanding member or post 14 is an end portion of a rearwardly directed arm 17. The rear or free end portion of the arm 17 is slidably disposed through an upstanding bracket 18 carried by the lower frame F. Surrounding the arm 17 is a coil spring 19 which bears against the bracket 18 and also against a stop 20 mounted upon the arm 17 so that the spring 19 constantly urges the arm 17 to maintain the bottom wall 50 in its closed position. The stop 20 is adjustable lengthwise of the arm 17 so that the tension of the spring 19 may be regulated to best comply with the requirements of practice.

Extending outwardly from the member or beam 9 are elongated flat tines or slats 21 which receive the matter discharged within the basket 51 by the elevator mechanism E. At a desired point, intermediate their ends, 30 at 22, the transversely disposed reinforcing member 23 which also operates to maintain the tines or slats 21 in the desired spaced relation.

Pivotedly engaged, as at 24, to the member or post 14 is an end portion of a link 25, the opposite end portion of said link being pivotally engaged, as at 26, to the lower end portion of an upstanding arm 27. The upper portion of the arm 27 is provided with an outstanding lug 28 which is pivotally engaged, as at 29, with the adjacent boxing or housing 47.

Secured to the periphery of the adjacent wheel 49 is an outstanding trip member 30 which, as the shaft 46 rotates, is adapted to contact with the upper end of the member or arm 27. Normally, or when the bottom wall 50 is free of load, the arm 27 is positioned out of the path of travel of the trip 30. However, as the weight of the material deposited within the basket 51 from the elevator mechanism E increases the bottom 50, under the influence of such weight of the load thereon, will drop downwardly and which movement results in a forward swinging movement of each of the members or posts 14 into the path of travel of the trip 30 so that as the shaft 46 continues to rotate, the trip 30 will swing the arm 27 downwardly and outwardly resulting in pull being imposed upon the coacting member or post 14 and whereby the bottom wall 50 is swung downwardly a distance sufficient to discharge the load thereon. As the shaft 46

continues to rotate, the trip 30 will pass out of engagement with the arm 27 whereupon the springs 19 will operate to effect an automatic return of the bottom wall 50 into closed position.

The upward swinging movement of the bottom 50 and as imparted thereto by the springs 19, is limited by contact of the lower end portion of each of the offset portions 10 with a bracket 31 depending from the lower portion of a block 1 and rearwardly of the coacting offset portion 10. When the bottom wall 50 is automatically returned by the springs 19, the offset portions 10 will contact with the depending brackets 31 whereby the bottom wall 50 is held in desired closed position.

From the foregoing description it is thought to be obvious that a dumping basket constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A dumping basket provided with a bottom wall movable into open and closed position, means for normally maintaining said bottom wall in closed position, a driven element, and coacting means carried by the bottom wall of the basket and the driven element for moving the bottom wall into open position, said coacting means being normally inactive, said bottom wall having independent movement under load for rendering said coacting means active.

2. A dumping basket provided with a swinging bottom wall, spring means for normally urging the bottom wall into closed position, a movable trip, a member operatively connected with the bottom wall, movement of the member in one direction swinging the bottom wall into open position, said member being normally out of the path of travel of the trip, said member when the load on the bottom wall of the basket reaches a predetermined weight being moved by the bottom wall into the path of travel of the trip.

3. A dumping basket provided with a wall movable into open and closed position, a driven element, means for normally maintaining the wall in closed position, normally inactive means coacting with the driven element for moving the wall into open position, and means operating under the in-

fluence of the weight of the load received within the basket for rendering active said normally inactive means.

4. A dumping basket provided with a wall movable into open and closed position, a driven element, and means operated by the driven element under the influence of the load received within the basket for moving the wall into open position.
- 10 5. A dumping basket provided with a wall movable into open and closed position, a driven element, and means operated at pre-determined intervals by the driven element for moving said wall into open position.
- 15 6. A dumping basket provided with a bottom wall movable into open and closed position, means for normally maintaining said bottom wall in closed position, a driven element and co-acting means carried by the bottom wall of the basket and the driven element for moving the bottom wall into open position, the means for normally maintaining said bottom wall in closed position also maintaining the co-acting means nor-
20 mally inactive, said bottom wall having in-
dependent movement under load for render-
ing said co-acting means active.
- 25 7. A dumping basket provided with a bot-
tom wall movable into open and closed posi-
30 tion, means for normally maintaining said
- bottom wall in closed position, a trip, means for driving said trip, an arm supported for swinging movement and positioned adjacent the path of travel of the trip, and an operative connection between the arm and bottom wall to position the arm out of the path of travel of the trip when the bottom wall is in its normal position and to swing the arm in the path of travel of the trip under the influence of weight imposed upon the bottom wall.
8. A dumping basket provided with a swinging bottom wall, a post carried by the bottom wall adjacent its mounting, a rotatable member provided with a trip, means for rotating said member, an arm positioned adjacent the rotating element and supported for swinging movement, a link connecting the swinging arm and post, and means for normally maintaining said bottom wall in a closed position, said link when the bottom wall is in its closed position moving the arm out of the path of travel of the trip and moving said arm into the path of travel of the trip under the influence of weight im-
posed upon the bottom wall.

In testimony whereof I hereunto affix my signature.

SPENCER B. WILLIAMS.
